UNITED STATES PATENT OFFICE.

HENRY KOCOUREK, OF CHICAGO, ILLINOIS, ASSIGNOR TO CHICAGO FLEXIBLE SHAFT COMPANY, OF CHICAGO, ILLINOIS, A CORPORATION OF ILLINOIS.

TERMINAL PLUG AND SHEATH FOR ELECTRIC CABLES.

Application filed October 22, 1926. Serial No. 143,486.

The purpose of this invention is to provide a sheath which shall be adapted for secure attachment to the terminal plug of an electric cable connection without requiring 5 enlargement of the latter, while at the same time affording ample clearance within this sheath around the cable to avoid chafing the insulating covering in the flexure of the cable and sheath, and in such flexure to permit the cable to bend in a curve of greater 10 radius than that of the bend of the sheath.

The invention consists in the elements and features of construction shown and described as indicated in the claim.

15 In the drawings:

Figure 1 is a section, axial with respect to the electric cable, of a terminal plug for such cable equipped with a sheath in a manner exemplifying this invention.

20 Figure 2 is a dissected view presenting in axial section the plug body, coupling bushing, adjacent terminal of the sheath, and the securing nut.

Figure 3 is a detail section on the line, 25 3—3, of Figure 1, showing the parts upon a magnified scale.

Figure 4 is a diagrammatic view for illustrating the effect of the construction for avoiding abrupt bending of the conducting 30 wires in flexing the cable at the part protected by the sheath.

Figure 5 is a section at line 5—5 on Figure 3.

In the structure shown in the drawings, A 35 is an insulating body of the terminal plug of an electric coupling cable of conventional form, commonly employed for coupling to an electric iron or other electrical heating device. B is the electric cable having 40 inleading and outleading wires, 10 and 11, secured in the usual manner to separate contact sockets, 12 and 13, carried by the plug, C is a bushing having intermediate its ends an encompassing boss, 15, and adapted at 45 the end portion, 16, to be engaged with the plug body, A, as by being screwed at said end portion into the hub or end boss, a, of the body, being stopped longitudinally by the shoulder, 15^a, of the annular flange or 50 boss, 15, the bushing having the opposite end portion threaded as seen at 18. D is the sheath made of coiled spring wire having 55 a limited number of coils, as seen at 20, of diameter to admit the cable and fit it rather closely so as not to defeat easy lon-

gitudinal movement, the sheath being continued from these close coils at the outer end portion any desired length of the cable, but as the plug-connected end of the sheath is approached the coils are gradually increased in diameter, rendering the sheath exteriorly and interiorly tapered, as seen at 60 21, this tapered portion being followed by a portion, 22, in which the coils are close and of successively increasing diameter, 65 continuing to taper until the interior diameter becomes such that the close coils constitute an interior thread adapted to engage the exterior thread 18 of the bushing, and when this diameter is reached the remaining coils, 23, to the end are of uniform diameter; and it will be understood that this thread, 18, of the bushing is formed, as to pitch and depth, so as to be fitted to co-operate 70 screwwise with the close coiled terminal part, 23, of the sheath. E is a nut diametered for being passed onto the sheath from the smaller end, adapted to engage the close coiled portion, 23, of the sheath at the larger end, and threaded for screwing onto said close coiled part up to the shoulder, 15^b, of the bushing, 15. By this means the sheath is rendered inseparable from the plug by any screw action which the sheath may receive; for it will be observed that the direction in which the sheath would have to be 75 rotated to unscrew it from between the bushing and the nut is the direction for tightening and the nut is the direction for reducing the diameter of the coil, and such tightening makes 80 the grip of the coil upon the thread of the bushing tighter and tighter as force is applied for attempting to thus rotate the sheath between the bushing and the nut. This expedient for securing the sheath to the 85 plug avoids any necessity for enlargement of the hub, a, of the plug body to afford engagement of the sheath within the latter, as is common construction for securing the sheath to the plug body, and avoids weakening the hub or end boss with which the plug body may be provided for like purpose by aperturing it for the engagement of the sheath wire to effect connection. At the 90 same time it will be observed that the enlargement of the coil diameter at the end portion at which the plug is attached for screwing outside the bushing permits the cable, when the sheath is flexed as required by the service of the implement to which it 100 105 110

is connected, to normally assume a curve of greater radius than that of the inner side of the bend of the sheath, as seen in Figure 4; and by this means abrupt bending of the cable at its emergence from the plug body is prevented.

I claim:

In a device for the purpose stated, in combination with the plug body a bushing adapted at one end for securement to said body, a protruding end portion being exteriorly threaded; a coiled wire sheath for an electric conducting cable having its coils successively increasing in diameter so as to render the sheath taperingly enlarged toward one end and having the extreme end

portion following said taperingly enlarged part coiled close and of uniform diameter, the exterior thread of the bushing being conformed to said close-coiled uniform diametered end portion of the sheath for receiving the latter as a female thread, and a nut diametered for passing over the coiled sheath from the smaller end of the tapered part and threaded for screw engagement with and outside of the uniform diametered close-coiled end portion of the sheath inside which the bushing is screwed.

In testimony whereof, I have hereunto set my hand at Chicago, Illinois, this 20th day of October, 1926.

HENRY KOCOUREK.
